G. W. WILSON

LIQUID CIRCULATING APPARATUS FOR INTERNAL COMBUSTION MOTORS

Filed March 3, 1926

UNITED STATES PATENT OFFICE.

GEORGE W. WILSON, OF ALGONA, IOWA.

LIQUID-CIRCULATING APPARATUS FOR INTERNAL-COMBUSTION MOTORS.

Application filed March 3, 1926. Serial No. 91,969.

This invention relates to an improved water pump, designed to be installed in the liquid circulating system of an automobile, being especially, although not necessarily, 5 designed for use on Fords.

The principal object of this invention is to provide a simple, economical and durable water pump which is such in construction that it can be installed by inexperienced 10 persons.

A further object is to provide a pump of the class under consideration which is driven by the fan belt of the engine and which communicates with water ways in the 15 cylinder block and is secured to the cylinder block in the same manner and by the same studs that originally served to retain the water return pipe in position.

A further object is to provide a water 20 pump which will support the electric horn of the automobile either for models before or after the year 1925.

A further object is to provide a water pump which may readily be taken apart 25 for repairs or adjustment.

These and other objects will be apparent to those skilled in the art.

My invention consists in the construction, arrangement and combination of the various 30 parts of the device, whereby the objects contemplated are attained as hereinafter more fully set forth, pointed out in my claims and illustrated in the accompanying drawings, in which:

Fig. 1 is a side view of my complete device ready for use and mounted on an internal combustion motor with parts cut away to more fully illustrate the same.

Fig. 2 is a top plan view of my water 40 pump mounted on an internal combustion motor with sections cut away to more fully illustrate the same.

Fig. 3 is an end sectional view taken on line 3—3 of Fig. 1 and shows the rotor 45 mounted in the pump casing.

Fig. 4 is a sectional view taken on line 4—4 of Fig. 1 and shows the means of actuating the pump.

Fig. 5 is a back view of an electric horn 50 for models prior to the year 1925 and shows the manner of securing the same to the top of the cylinder casing and my improved water pump.

Fig. 6 is a side view of an electric horn 55 for models during and since the year 1925

and shows the manner of securing the same to my improved water pump.

The thermo-siphon cooling system, such as is extensively used in connection with internal combustion motors at the present 60 time, is not effective in maintaining the engine at a proper temperature under all conditions of service, due to the fact that the cooling liquid circulates through the system very slowly and hence the engine heats up 65 rapidly, and is further not effective due to the fact that all circulation in the system ceases upon a drop in the level of the cooling liquid to a point below the radiator inlet. Two classes of devices have been designed to 70 overcome these defects by forcing the circulation of the cooling liquid, one class of said devices utilizing the exhaust of the engine while the other class utilizes a mechanical impelling device. My device relates to the 75 last mentioned class.

In mounting the mechanical impelling devices now on the market to the cylinder block, the position of the electric horn is 80 obstructed. I have also overcome this objection as will hereafter be explained.

I have used the numeral 10 to designate the ordinary internal combustion motor having water ways for keeping the same cool. At the top of the engine and communicating 85 with the water ways and radiator 11 is the circulation elbow 12. Rotatably mounted on the fan shaft 13 and back of the radiator is the fan 14. The numeral 15 designates an endless belt in engagement with the crank 90 shaft 16 of the engine and the fan 14. In the side of the cylinder blocks of the engine is a port 17 communicating with the water ways around the cylinders. Ordinarily this port is also in direct communication by a 95 conduit to the bottom of the radiator 11. It is between this port and the bottom of the radiator that I install my improved pump.

The numeral 18 designates the cylindrical 100 pump casing forming the main body of the attachment and having the inlet pipe 19 and outlet pipe 20 integrally formed thereon. Closing the back end of the casing 18, and secured thereto by the screws 21 is the cover 105 plate 22. The pump is secured to the cylinder block of the engine and in communication with the port 17 by having the studs 23 passing through holes in the flange 24 which is integrally formed on the rim of the outlet pipe 20, and threaded into the cylinder 110

block. Originally these studs held the ordinary water connection which was in communication with the bottom of the radiator. Forwardly and outwardly extending and integrally formed on the flange 24 is the arm 25 having integrally formed on its end the bearing member 26. Inside this bearing member 26 is a wooden bearing 27. The front end of the pump casing 18 is restricted 10 and forms a bearing member 18' which has threaded into its opening the gland 28. Passing through the wooden bearing 27, the gland 28 and into the pump casing is the pump driving shaft 29 journaled for rotation. On the end of the shaft 29 within the pump casing is the rotor 30. On the other end of the shaft 29 is the pulley wheel 31 designed to engage the fan belt 15 as is shown in Fig. 4 and Fig. 1. This pulley 20 wheel may be slid on the shaft 29 to a position where it is in proper alignment with the fan belt. Once it is in proper alignment it may be secured against any relative movement to the shaft by tightening the set screw 32. To prevent the shaft 29 from being pulled from the pump casing a collar 33 is provided and is secured to the shaft by the set screw 34 and positioned adjacent the bearing member 26 as is shown in Fig. 2. 30 To prevent unnecessary friction a washer 35, preferably made of wood, is placed between the collar 33 and the bearing member 26. The numeral 36 designates a rubber hose employed to secure the pipe 37 to the inlet pipe 19, and the numeral 38 a second rubber 35 hose employed to secure the pipe 37 to the bottom of the radiator.

It will now readily be seen that if the engine is running, the shaft 29 will be rotated; which in turn rotates the rotor 30. This action draws the cooling liquid from the bottom of the radiator and deposits the same into the port 17, thus forcing the circulation of the cooling medium.

To prevent the leakage of the cooling medium from the front end of the pump casing, packing 39 is placed in the bearing member 18' and around the shaft 29. This packing is held in place by the shoulder 40 in the bearing member 18' and the gland 28. By screwing the gland 28 to the right the packing will be compressed and held tightly around the shaft and against the bore of the bearing member.

To guard against unnecessary movement and possible displacement of the device after it is once positioned, and also to decidedly increase the rigidity, I make use of the stud 41 in the arm 25, which is designed to be brought against the cylinder block. This stud is held against rotation by the lock nut 42.

In the bottom of the pump casing and communicating with the inlet pipe 19 is the hole 43. This hole is provided so that when

the radiator is drained to prevent freezing, the pump casing will also be completely drained. Thus no water will remain in the casing and freeze and hinder the effective rotation of the member 30.

When the device is installed on automobiles purchased before 1925 and having the old style electric horn bracket 44, the same is bent outwardly as is shown in Fig. 5 until the lower portion of the bracket embraces the lug 45 integrally formed on pump casing. This end of the bracket is held on the lug 45 by the stud 46 passing through the same and threaded into the said lug.

When the device is installed on automobiles having the new style electric horn bracket 47, the same is secured to the water pump by the stud 48 passing through the bracket and threaded into the projection 49 integrally formed on the pump casing, and the stud 50 also passing through the bracket and threaded into the ear 51 formed on cover plate 22, as is shown in Fig. 6.

I have used the numeral 52 to designate the ordinary electric horn.

Some changes may be made in construction and arrangement of my liquid circulating apparatus for internal combustion motors without departing from the real spirit and purpose of my invention and it is my intention to cover by my claims any modified forms of structure or use of mechanical equivalents which may be reasonably included within their scope.

I claim:

1. In combination with an internal combustion motor having a water jacket, a radiator, connections therebetween and an electric horn bracket, and a centrifugal fluid pump unit comprising a pump casing, an inlet pipe communicating with the radiator and pump casing, an outlet pipe communicating with the pump casing and water jacket, a rotor inside said casing, a means for propelling said rotor, a lug integrally formed on said casing and designed to engage one end of said horn bracket, and a stud for securing the said end of the horn bracket to the said lug.

2. In combination with an internal combustion motor having a water jacket, a radiator, connections therebetween and an electric horn bracket, and a centrifugal fluid pump unit comprising a pump casing, an inlet pipe communicating with the radiator and pump casing, an outlet pipe communicating with the pump casing and a port in the water jacket, a rotor inside said casing, a means for propelling said rotor, a lug integrally formed on the pump casing, an ear formed on the pump unit, and studs threaded into said lug and ear and designed to hold the said horn bracket on the same.

3. In combination with an internal combustion motor having a water jacket, a

radiator and an electric horn bracket, and a fluid pump unit, said fluid pump unit being in communication with the said radiator and a port in the water jacket, an upwardly 5 extending lug formed on said pump unit designed to engage one end of said horn bracket when the other end is secured to the water jacket of the engine, a stud for securing the first mentioned end of said 10 bracket to said lug, a second lug formed on the pump unit extending outwardly, a third lug formed on the pump unit; said last two lugs designed to engage both ends of a horn 15 bracket when one of its ends is not secured to the water jacket, and studs for holding

said horn bracket to said last two mentioned lugs, for the purpose stated.

4. The combination with an internal combustion motor having a horn bracket normally attached thereto, of a liquid circulating apparatus adapted to be mounted at the side of said motor, said apparatus including a pump unit for assisting in the circulation of water through the waterways of the motor, said pump unit having an enlargement thereon formed with a threaded seat, and a cap screw for attaching said horn bracket to said threaded seat. 20 25

GEORGE W. WILSON.
